UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

HEEL-BUILDING MACHINE.

Application filed July 19, 1919. Serial No. 311,968.

To all whom it may concern:

Be it known that I, ERASTUS E. WINKLEY, a citizen of the United States, residing at Lynn, in the county of Essex and State of Massachusetts, have invented certain Improvements in Heel-Building Machines, of which the following description, in connection with the accompanying drawings, is a specification, like reference characters on the drawings indicating like parts in the several figures.

This invention relates to heel building machines, and more particularly to that type of heel building machine whereby a plurality of lifts or pieces of leather, or other material, are fastened together to form a heel.

Heretofore it has been the common practice to build heels by manually assembling a number of lifts, one on top of the other, in a mold, and fastening them together by one or more fastenings or nails driven into the pile of lifts while under pressure. In the operation of heel building, the height of the resultant heel has depended upon the skill and care of the machine attendant in placing the required number of lifts of proper thickness in the mold, and, as a result, heels of a series have not been uniform.

Lack of uniformity in the height of successive heels in a run of heels, and the objections thereto, may manifest themselves not only after the heels are attached to the boots or shoes, but also during the treatment to which the built-up heels are subjected after or before leaving the heel building machine. For instance, the heel lifts have their contact surfaces provided with an adhesive or glue, and in order that the contour edges of the lifts may be held in close contact when the heel is finished, the built-up heel is placed in a heel press where the heel is subjected to pressure for a time sufficiently long to enable the glue or adhesive to set or become dry. If, however, the heels built in the heel building machine are not of the proper height, or too low, the fastenings or nails which secure the lifts together, may not be driven completely into the pile of lifts, and such projecting nails will not permit the heel lifts to receive the desired uniform pressure of the clamps when in the heel press. This may result in cracks appearing between the heel lifts when attached to the boot or shoe and finished, or worn.

Attempts have been made to overcome this objectionable variation in the height of built-up heels produced in the heel-building machine, by the use of gage plates arranged in piles about the support for the heel lifts, so that the machine attendant could feel the gage plates with one hand, and with the other hand select the lift or lifts of the proper thickness to bring the heel up to the desired height. In this, as in the older method, however, the care and skill of the machine attendant determines the height of the pile of lifts, and, consequently, variations in the heights of the heels result.

A more satisfactory solution of the problem, however, is furnished by the machine of the United States patent to John R. Richardson No. 1,148,716, dated August 3, 1915, wherein automatic means is provided for measuring the height of the pile of heels assembled for treatment in the heel builder. In this machine a measuring means acts to measure the pile of lifts before they are put under pressure, and if the pile is not in accordance with a predetermined standard, operation of the securing means is prevented, and the attendant may correct the inaccuracy. This has resulted in a greater uniformity in the height of a run of built-up heels, and is satisfactory and efficient in operation. It is desirable, however, that the height of the finally completed or compressed pile of heel lifts may be uniform, and if not that the fastenings or nails be not driven into the pile of lifts to secure them together. The material of the lifts, for instance, may not always be uniform in character, so that while successive piles of heel lifts may measure the same height before they are subjected to pressure, they may vary in height after compression.

An important feature of the present invention, therefore, consists of means for preventing the operation of the securing means when a pile of heel lifts under compression does not conform to a predetermined standard. The consequence of this is that when the machine is adjusted for building heels of a certain height and securing the lifts together only when the pile of compressed lifts corresponds to a predetermined height, successive heels treated by the machine will be of substantially the same height.

When the heel lifts are placed in the heel-building machine, they are usually posi-

- tioned relative to the front of the machine by the heel breast which bears against a breast gage or finger. Some machine attendants prefer to have the heel breast facing towards the rear of the machine or away from them, others prefer that the heel breast be facing towards the side of the machine, and still others prefer it facing the front. These various preferences are incidental to individual characteristics which enable the attendant to place the heel lifts in position for treatment with greater facility when the breast of the heel faces in some particular direction.
- Another important feature of the present invention, therefore, consists in providing a lift support which may be adjusted into different lift assembling positions to place the breast gage so that it shall face in different directions relative to the front of the machine. This feature of the invention may be variously contrived, but in the present instance, as will more fully appear, the lift support is mounted for rotative movement, and means are provided for securing the lift support in desired position of rotative movement to place the breast gage in the desired location.

As hereinbefore noted, the contacting faces of the heel lifts are commonly supplied with a glue or adhesive, portions of which, during the pressure to which the pile of lifts is subjected, is discharged from between the lifts. The glue thus discharged form the pile of lifts is liable to drop upon the operating parts of the machine and cause improper operation and wear or breakage of parts. Another important feature of the invention, therefore, consists of providing a receptacle beneath the heel lift support and surrounding the fastening inserting, or driver, mechanism for catching the adhesive or glue expressed from the lifts when subjected to pressure, in combination with a deflector to deflect the adhesive or glue away from the operating parts into the receptacle.

The invention further consists in certain features of construction and novel combinations of parts, which will be hereinafter described in the specification and in addition to the above, pointed out in the claims.

In the drawings:

Fig. 1 is a side view of a heel building machine containing the present invention;

Fig. 2 is a front elevation and section on the line 2—2 of Fig. 1;

Fig. 3 is an enlarged section on the line 3—3 of Fig. 2;

Fig. 4 is an enlarged section on the line 4—4 of Fig. 2;

Fig. 5 is a detached detail showing the presser cam and parts of the measuring device, some of the elements being shown in section;

Fig. 6 is a detached enlarged detail showing the presser cam and parts of the measuring means in separated relation, some of the parts being shown in section.

The general character of the heel-building machine to which the present invention may be advantageously applied, may vary considerably, but in the present instance, a machine of the manually operable type is illustrated as a convenient means for explanation of the invention and its cooperative relation with parts of the machine.

The supporting frame may be of any usual character suitable for sustaining the operating parts and as shown comprises a base portion 1 from which rises the column 2 provided with bearings 3, 4, in which is mounted the reciprocating rod 5 constituting part of the fastener-inserting or nail-driving mechanism. The rod 5 has secured to it a lug 6 to which is pivotally connected at 7, 7, the rods 8, the lower ends of which are connected at 9, 9, with an arm 10 of a bell crank lever pivotally mounted on the machine frame at 11. The other arm 12 of the bell crank or rocking lever is connected by a link 13 to an arm 14 secured to a rock shaft 15, mounted in the lower part of the machine frame and having secured thereto the treadle 16, the construction being such that by depression of the treadle 16 the rod 5, heretofore described, will be moved upwardly for inserting the fastening, or driving the nail or nails.

The column 2 supports at its upper portion a head 17 to which is bolted at 18 the bent arm 19 which constitutes the support for the upper presser member, as will more fully appear.

Above the head 17 is secured the receptacle 20 provided with a bearing portion 21 through which the upper extension of the rod 5 passes. The bearing portion 21 which may be connected to the receptacle 20 in a manner to provide an adhesive or glue containing portion 22, extends some distance above the bottom or lower portion 23 of the receptacle 20, the construction being such that any adhesive or glue dropping from the heel lifts or running therefrom during the compression thereof, may drop within the receptacle 20 and be sustained in the space 22 without danger of coming in contact with the operating parts of the machine, and more particularly the reciprocating rod 5.

The upper end portion of the receptacle 20 serves to support a plate 24 which may constitute a form of table. The support 24 may be connected to the top of the receptacle 20 by the flanges 25, and suitable securing means may be provided for holding the support 24 and receptacle 20 in associated relation.

The support 24 has a hub portion 26 in

which is mounted a nail block 27, the upper end portion of which is provided with a flange 28 which rests upon the upper end of the hub portion 26 and may there be secured in fixed position. The nail block 27 is provided with a passage way or passage ways for the fastening or nails, and driver or drivers. In the present instance of the invention only one driver is shown, and, 10 therefore, only one fastener or nail is driven into the heel lifts to secure them together, but it is to be understood, of course, that the number of drivers and fasteners or nails may be varied to suit conditions.

15 The upper end portion of the reciprocating rod 5 is provided with a socket in which is received the stud 29, Fig. 4, of the driver head 30. The driver head is provided with a cap 31 for securing thereto the driver 32, 20 which extends upwardly from the driver head and enters the nail block, as indicated in Fig. 3. The cap 31 may be secured to the driver head 30 by appropriate means, such as the bolts 33.

25 Mounted upon the top of the support 24 is the lift support 34, Fig. 3, which, in the present instance of the invention, is of general circular shape in plan and mounted for rotative movement about the axis of 30 the nail block. A series of holes or threaded openings 35 formed in the support 24 at intervals, enables the lift support 34 to be rotated about the axis of the nail block 27 and secured in rotated or adjusted position 35 by suitable means, such as the bolt 36, Fig. 3. In the present instance of the invention the lift support 34 has adjustably secured thereto the breast gage 37 and the side gages 38 which are secured in desired relation of 40 adjustment to accommodate the heel lifts which are to be secured together. The breast gage may be variously secured to the lift support and rotate with it, and in the present instance, is shown as provided with a slot 39 45 in the lower foot portion of the gage through which extends the bolt 40, the construction being such that by loosening the securing bolt 40 the breast gage may be adjusted relatively to the side gages to accommodate the 50 heel lifts which are to be treated. The side gages 38, or fingers as they are sometimes called, may also be secured to the lift support 34 adjustably, as by means of the bolts 41, one of which is indicated in Fig. 3.

55 When the machine attendant desires to have the breast gage 37 in position facing to the rear of the machine, he or she turns the lift support 34 until the breast gage 37 is in the desired location and thereupon secures the lift support 34 in position by means 60 of the securing bolt 36. If, on the other hand, the machine attendant should desire the breast gage 37 to be located towards the front of the machine, in order to facilitate 65 the piling of the lifts upon the lift support,

he or she unscrews the bolt 36, turns the lift support 180° from the position indicated in Fig. 3, and then secures the parts in the new position by means of the bolt 36.

The arm 19, which constitutes one convenient means for supporting the upper presser member, is provided with a hub portion 42, Fig. 3, in which is mounted a plunger 43 having an enlarged head 44 between which and the lower end of the enlarged 75 chamber 45 in the hub, is the spring 46, normally tending to lift the plunger 43. The head 44 on the plunger 43 may be held in position by suitable means such, for instance, as a cap piece 47 threaded into the upper end of the plunger and affording a surface against which may act the presser cam 48.

The lower end portion of the plunger 43 is provided with a threaded recess 49 in 85 which is adjustably mounted the presser stem 50 carrying the presser 51, which constitutes one of the presser members for exerting pressure upon the heel lifts placed between them. In order to prevent rotative 90 movement of the plunger 43 as it is reciprocated in its support, the lower end portion of the plunger 43 has secured thereto an arm 52, carrying a pin 53 which rides in a socket 54 as the plunger is reciprocated. Suitable 95 means may be provided for preventing rotative movement of the adjusting stem 50 of the presser to prevent disturbance of adjustment during reciprocation of the plunger.

Rising from the arm 19 are the supports 100 55, best shown in Fig. 2, between which is mounted the supporting pin or shaft 56. Mounted upon the supporting pin or shaft 56 is the presser cam 48 which constitutes one convenient form of means for applying 105 pressure to the heel lifts through the upper presser member. The presser cam 48 has its presser surface 57 adapted to contact with the head or cap portion 47 of the plunger 43, the construction being such that 110 upon rotative movement of the cam 48 contraclockwise, viewing Fig. 3, the plunger 43 will be depressed.

The pressure cam 48 is provided with a socketed or recessed portion 58 in which is 115 mounted a spring 59, one end of which, at 60, rests against the end wall of the socket or recess and the other end 61 of which rests upon a lug 62 carried by a segment portion 63 of the cam actuating means, which, in the 120 present instance of the invention, comprises a handle 64 and yoke 65 having a hub portion 66 mounted on the stud or shaft 56, the construction being such that upon movement of the handle 64 in contraclockwise direction, viewing Fig. 3, and Fig. 6, the lug 62 125 will act through the spring 59 to rotate the presser cam 48.

When the presser cam has been rotated to an extent to produce the desired pressure 130

upon the heel lifts mounted on the lift support, and the pile of heel lifts has been compressed, it is desirable that the height of the compressed pile of lifts may be measured, and if either too high or too low, that the fastening or nail be not driven into the pile of lifts to secure them together.

Pivottally mounted at 66 on the machine frame, or, as in the present instance, upon 10 the arm 19, is the measuring lever 67, the lower end 68 of which engages a locking member which, under certain conditions, to be hereinafter described, prevents operation of the heel lift securing means or 15 driver. In the present instance of the invention the locking means consists of a slide 69 mounted for reciprocating movement in a bearing 70 sustained upon the machine frame, and connected to the lower end of the 20 measuring arm 67. The connection between the measuring arm 67 and the slide 69, in the present instance, consists of a slot 71 formed in the end of the slide 69 through which the end 68 of the measuring lever ex- 25 tends, the construction being such that should the measuring lever 67 be moved about its pivot 66, the slide 69 will be reciprocated.

Mounted upon the rod 5, which, as here- 30 tofore explained, constitutes part of the operating mechanism of the securing means, is a stop collar 72 which may be secured in desired position on the rod by means of a set screw 73, Fig. 4. The collar 72 has a 35 flange 74 which, when the rod 5 is in its lowered or inoperative position, is below the end of the slide 69, as indicated in Fig. 1, so that the rod 5 cannot be raised when the slide 65 is extended inwardly over the flange 40 74, as indicated in Fig. 1, and, perforce, the securing means or driver cannot be actuated.

The presser cam 48 carries a lug 75, Fig. 6, having a beveled surface 76 which is adapted to be engaged by a reversely beveled surface 45 77 on a lug 78 extending from the segment 63, the construction being such that the spring 59 normally maintains the beveled surfaces 76 and 77 in contact.

The measuring lever 67, hereinbefore referred to, has an upwardly extending arm 79 provided with a roller or side extending pin 80 which is adapted to rest upon the contour or peripheral surfaces of the lugs 75 and 78 when the parts are in closed or 55 normal position. When the presser cam 48 is in a position of pressure and the pile of compressed heel lifts conform to a predetermined standard, the roll 80 on the measuring arm rests at the junction between the 60 lugs 75 and 78, and as the cam actuating means, in this instance the handle 64, is further turned, the lug 62 is moved against the tension of the spring 59 while the presser cam 48 remains fixed, the effect being that 65 the lugs 75 and 78 are separated and the

roll 80 may move inwardly under the impulse of the spring 79*, as indicated in Fig. 3, thereby withdrawing the slide 69 from above the flange 74 of the sleeve 72 and permitting operation of the securing means or driver. If, however, the pile of lifts is too high when the presser cam 48 is actuated to impart pressure thereto, the position of the lug 78, while separating from the lug 75, will be such as to interrupt the inward movement of the roll 80 and, perforce, withdrawal of the slide 69 from its locking position. The result is that under the conditions stated, the securing means or driver cannot be operated and the fastening or nail will not be driven. On the other hand, should the pile of heel lifts be too low, the presser cam 48 will be moved farther than when the lifts are of the proper height, and will interject the projection 75 into the path of movement of the roll 80, with the result that again the slide 69 will remain in locking position and prevent operation of the securing means or driver. Thus it will be seen that the measuring means measures or determines the height of the pile of lifts while they are under pressure and if the pile of lifts be either too high or too low when under pressure, the measuring device will prevent operation of the securing means or driver.

When the pile of compressed heel lifts conforms to the predetermined standard, and the measuring device therefore permits operation of the securing means or driver 100 by inward movement of the roll 80, it is necessary to move the roll 80 outwardly to restore the measuring device to its normal position after the fastening or nail has been driven and when the presser cam is moved 105 to its non-pressing position. To effect this the present invention provides the yoke 65* to which the handle 64 is connected, with a setting cam 81 which, as the handle 64 is moved clockwise from the position of Fig. 110 3 to that of Fig. 5, acts upon the roll 80 to move it outwardly, as indicated in Fig. 5, and past the tip end portion of a pawl 82 pivoted at 83 to the segment 63, whereupon a spring 84 acting on the pawl, snaps it back 115 into its normal position with the end of the pawl resting against the cam 81, as indicated in Fig. 3. When the pawl has snapped back into position against the cam 81, after the passage of the roll 80, the contour surface of the pawl forms a track on which the roll 80 rides as the presser cam is moved into presser position as indicated in Fig. 3.

Should the adhesive or glue which is expelled from between the heel lifts while 125 under pressure, find its way to the pressure operating means, such as the rod 5, such adhesive or glue may adhere thereto with such tenacity as to make it difficult to operate the securing or driving means. To in- 130

sure against such interference, the rod 5, within the receptacle 20, is provided with a deflector 85, Fig. 4, which may be conveniently formed as part of the driver head 30, so that should any adhesive or glue drop downwardly into the receptacle 20 it will be deflected outwardly from the rod 5 into the lower portion of the receptacle where all danger of interference with the securing 10 means or driver is avoided.

While the present invention has special advantages in connection with a heel building machine of the general type herein described, it is not restricted thereto, but may 15 be employed with advantageous results in connection with other forms of heel building machine to produce compressed heels of uniform height throughout the series.

Having described the invention, what is 20 claimed as new and desired to be secured by Letters Patent of the United States is:—

1. In a heel building machine, the combination of a heel mold, an opposed presser member, means for relatively moving the 25 mold and presser member to apply pressure to a pile of heel lifts assembled in the mold, means for securing the pile of lifts together, and means for preventing operation of the securing means when the pile of heel lifts, 30 while under pressure, does not conform to a predetermined standard.

2. In a heel building machine, the combination of a heel mold, an opposed presser member, means for relatively moving the 35 mold and presser member to apply pressure to a pile of heel lifts assembled in the mold, means for driving a fastening into the pile of lifts to secure them together, and means for preventing operation of the driving 40 means when the pile of lifts, while under pressure, fails to conform to a predetermined standard.

3. In a heel building machine, the combination of a heel mold, an opposed presser 45 member, means for relatively moving the mold and presser member to apply pressure to a pile of heel lifts assembled in the mold, means for securing the pile of lifts together, measuring means for determining the height 50 of the compressed pile of lifts, and means controlled thereby for preventing operation of the securing means when the compressed pile of heel lifts does not conform to a predetermined standard.

4. In a machine of the class described, the combination of a heel mold, an opposed presser member, means for relatively moving them to apply pressure to a pile of lifts assembled in the mold, means for driving a 55 fastening into the work while under pressure, and means for measuring the work after it is subjected to pressure and acting to prevent operation of the driving means when the pressed work does not conform to 60 a predetermined standard.

5. In a heel building machine, the combination of a heel mold, means for securing together a pile of heel lifts placed in said mold, means for subjecting the pile of lifts to pressure, measuring means for measuring 70 the height of the pile of lifts after they have been subjected to pressure, and means controlled by the measuring means for preventing operating of the securing means when the measured height of the compressed 75 pile of heel lifts is either too low or too high.

6. In a heel building machine, the combination of a heel mold, an opposed presser member, means for relatively moving the mold and presser member to apply pressure 80 to a pile of heel lifts assembled in the mold, adjusting means for adapting the presser member to apply pressure to piles of lifts of different height, means for driving a fastening into the pile of lifts to secure them together, and means for preventing operation 85 of the driving means when the pile of lifts while under pressure fails to conform to a predetermined standard.

7. In a machine of the class described, the combination of a heel mold, an opposed presser member, means for relatively moving the mold and presser in a direction of approach to subject a pile of heel lifts to pressure, driving means for driving a fastening 90 into the pile of lifts to secure them together, and means normally acting to prevent operation of the driving means and freeing it to operation when the measured height of the pile of lifts under pressure conforms to a 95 predetermined standard.

8. In a heel building machine, the combination of a lift support, fingers adjustably secured in position to contain heel lifts between them, a presser, a driver for driving a 100 fastening into the heel lifts, means for moving the presser to exert pressure on the heel lifts, and measuring means controlled by the presser moving means for preventing operation of the driver when the pile of heel lifts 110 after being compressed is either higher or lower than a predetermined standard.

9. In a heel building machine, the combination of a lift support, breast and side fingers for confining a pile of heel lifts, a 115 presser, means for operating the presser to exert pressure on the pile of lifts held between the fingers, and means permitting the lift support to be moved and secured in lift assembling position with the breast finger 120 facing in different directions relative to the front of the machine.

10. In a machine of the class described, the combination of a heel lift support, a breast gage for positioning heel lifts on the support, means for securing the lift support in lift assembling position with the breast gage 125 facing differently relative to the front of the machine, and means for subjecting heel lifts to pressure.

11. In a machine of the class described, the combination of a heel lift support mounted for rotary movement, a gage for determining the position of the heel lift on the support, means for securing the heel lift support in lift assembling position with the gage facing in different directions relative to the front of the machine, and means for subjecting the heel lift to pressure in any of its 10 positions.

12. In a heel compressing machine, the combination of a heel lift support and op-

posed presser for exerting pressure upon heel lifts on the support, a driver for driving a fastening into the heel lifts, means for operating the driver, a receptacle beneath the heel lift support for catching adhesive or glue expressed from the lifts when subjected to pressure, and a deflector movable with the driver for deflecting the adhesive or glue 15 into said receptacle.

In testimony whereof I have signed my name to this specification.

ERASTUS E. WINKLEY.
